INVENTOR

JOSEPH A. POCHÉ.

BY

Edward P. Thompson
ATTORNEY

UNITED STATES PATENT OFFICE.

JOSEPH A. POCHE, OF NEW ORLEANS, LOUISIANA.

ELECTRIC PROTECTOR FOR BUILDINGS.

SPECIFICATION forming part of Letters Patent No. 637,409, dated November 21, 1899.

Application filed April 21, 1899. Serial No. 713,938. (No model.)

To all whom it may concern:

Be it known that I, JOSEPH A. POCHE, a citizen of the United States of America, and a resident of New Orleans, in the parish of Orleans and State of Louisiana, have invented a new and useful Improvement in Electric Protectors for Buildings, of which the following is a specification.

My invention relates to mechanism for protecting buildings against the danger from fire caused by abnormal currents arising outside of the building—for example, when the lines become crossed while carrying currents of high potential with lines conducting low potential which operate translating devices inside the said building.

The invention will be understood by reference to the accompanying drawing.

The figure is a vertical section of the mechanism shown in elevation. Some of the parts are not in section.

The wall of the building is represented by the numeral 1.

2 is a mere outline of one of my insulators for passing a main conductor 2' through the wall 1 in an air and water tight manner and forming the subject-matter of prior patents and applications, but having nothing to do with the novelty of this invention.

3 is a hook supported to be turned to the left against the action of the spiral spring 4. The conductor 2' has a hook 2''. The hook 3 is held up by means of a fuse 5, which connects the two hooks 2'' and 3. At a, which is in the path of the rotary hook 3, is a cap to be exploded by the hammer 3' on the hook 3 when the fuses 5 melt.

At the lower part of the figure may be seen representations of substantial duplicates of the above-named elements, and accordingly they are similarly numbered, the only difference being that the conductor 2' in one case is a positive and in the other case a negative pole.

45 I will now follow the invention from the upper spring 4, the same forming a part of the circuit from the fuse 5 and lever 3. The conductor 6' connects the spring 4 to the binding-screw 6, attached to the frame 7. The 50 binding-screw 8 is connected through the metal frame 7 with the binding-screw 6 and also connects with the main line 9 inside the

building. The other main line inside the building is 13. Connecting the two lines is a very high resistance coil 10, forming a so- 55 lenoid.

11 is a choke-coil connected between the binding-post 8 and the post 12 of the line 13.

14 is a carbon-plate to which the binding-post 12 is attached. On the other edge of the 60 plate 14 is a binding-post 17, which connects with the lower spring 4, and so on with the outside line. The two posts 12 and 17 are connected together by the conductor 15.

22 is a rod having a carbon-terminal 18, the 65 holder 19 for the carbon being secured at the lower end of the rod 22, at the upper end of which is a trip-collar 23, attached thereto.

20 is an adjustable collar for adjusting the tension of a helical spring 22', arranged between said collar and the lower part of the frame 7 and tending to force the carbon-terminal 18 rapidly against the carbon-plate 14. The rod 22 is held up by the hook 24, whose degree of movement is regulated by the stop 75 at 25 and resisted by spring 25'.

26 is a bent trip-lever for releasing the hook 24 from the tripping-collar 23.

28 is an adjustable screw for adjusting the tension of the spring 28' upon the lever 26, 80 which is slotted to receive the pin 29' on the core 29 belonging to the solenoid 10.

32 is a cord having a handle 33 for operating the device manually when desired.

30 is a rack carried by the core 29 and engaging with a pinion 31 for turning the pointer 31, so that the condition of the device, whether it is normal or abnormal, may be known.

38 is a casing for the lower portions of the mechanism. On the top of this is an inverted 90 glass vessel 36, having a slot 29'' for the entrance of the hook 2''. Inside of the vessel 36 is a glass cylinder 37, open at both ends and having a slot 39' running its whole length.

34 and 35 are brackets attached to the wall 95 1 for holding the containing vessel 38.

The operation of the mechanism is as follows: When an abnormal voltage, sufficient to cause the armature of the electromagnetic device to move from its normal position, this 100 movement is transmitted by lever 26 to hook 24, which in turn trips the rod 22, and the tension of the spiral spring 22', in combination with the force of gravity, instantly forces

carbon-point 18 against carbon-plate 14 and short-circuits the main lines, and in consequence an abnormal rush of current passes through the fuses 5, which are of a predetermined carrying capacity, and which melt and release the hook-levers 3, which fall rapidly away from hooks 2, increasing the length of arc-gap to a point of safety and exploding caps to signal the occupants of said building so protected.

I claim as my invention—

1. A protector for automatically cutting out the interior wiring in a building from the outside wiring, consisting of the combination with fuses, of means, for producing a sound by concussion, located in the paths of said means, short-circuiting terminals included in circuit between said fuses and normally separated, and an electromagnetic device of high resistance included in circuit across the main line of the interior wiring for operating said terminals, and a manual device for adjusting said terminals.

2. A protector for automatically cutting out the interior wiring in a building from the outside wiring, consisting of the combination with fuses, in circuit with the outside and inside wiring, of levers held against the action of springs by said fuses, electric terminals,

normally separated and one of them movable, and in circuit between said fuses, a spring tending to press the terminals together, means for holding said terminals apart, against the action of said spring, a tripping-lever for operating said means, a solenoid in the electric circuit, and having a core provided with a pin which is located in a slot in said lever, and an indicator for showing the position of said core.

3. A protector for automatically cutting out the interior wiring in a building from the outside wiring, consisting of the combination with fuses, in circuit with the outside and inside wiring, of terminals normally separated and adapted to come together, a tripping-collar on one of the terminals, a lever upholding said terminal, a tripping device for releasing said lever from said collar, and an electromagnet controlling said tripping device, said lever being adjustable relatively, to said collar and to said device.

In testimony whereof I have hereunto subscribed my name this 18th day of April, 1899.
